C. DINUCCIO.
IDENTIFICATION RING.
APPLICATION FILED AUG. 5, 1910.

Patented Feb. 21, 1911.

UNITED STATES PATENT OFFICE.

CAMILLO DINUCCIO, OF PROVIDENCE, RHODE ISLAND.

IDENTIFICATION-RING.

984,803.

Specification of Letters Patent. Patented Feb. 21, 1911.

Application filed August 5, 1910. Serial No. 575,799.

To all whom it may concern:

Be it known that I, CAMILLO DINUCCIO, a citizen of the United States, residing at Providence, in the county of Providence and State of Rhode Island, have invented a new and useful Improvement in Identification-Rings, of which the following is a specification.

This invention relates to a certain new and useful improvement in identification rings, the ring being made in two parts and so arranged as to be capable of being secured together to have the appearance of one solid ring, the inner surface of one or both of the halves or parts of the rings being adapted to bear identifying or other matter, which may be engraved thereon, or otherwise marked.

The invention aims to provide a ring of this character which is of simple construction, and one in which the locking means for the ring halves may be operated with ease and facility, and may be unlocked in a corresponding manner.

Further and other objects will later appear.

In the drawings: Figure 1 is a top plan view of the ring showing the same in assembled form, Fig. 2 is an end elevation of the ring in its assembled form, Fig. 3 is a plan view of the two halves in their unlocked state, Fig. 4 is a similar view taken from the opposite side of Fig. 3, and Fig. 5 is a fragmentary cross section showing in detail the locking means.

The ring is composed of two halves or parts 1 and 2, each part being so formed that when the faces 3 and 4 of the parts are brought into contacting relation, as shown in Figs. 2 and 5 of the drawings, the completed ring will have a substantially circular or elliptical cross section as is usual in finger rings. The major portions of the halves 1 and 2 are semi-circular or semi-elliptical in cross section, in order that when the halves are brought together they conjointly form a complete circle or complete ellipse in cross section. The halves are also formed with a tortuous or compound groove 5 and 6 respectively, which grooves are formed in enlarged portions 7 and 8 respectively, the thickness of the enlarged parts 7 and 8 being equal to that of the completed ring as depicted in Fig. 2. The groove 5 extends from the face 3 on one side of the enlarged part 7 downwardly and outwardly, then inwardly

and upwardly, terminating at the inner face 3 on the opposite side of the enlarged part 7. Similarly the groove 6 extends from face 4 on one side of enlarged part 8, downwardly and outwardly, then inwardly and upwardly, terminating at the inner face 4 on the opposite side of the enlarged part 8. The grooves 5 and 6 it will thus be seen are somewhat of spiral shape.

When the ring is in assembled form the enlarged parts 7 and 8 by virtue of their groove formations perfectly interlock and form a joint of the type depicted in Fig. 2. In order to hold the parts in locked position the half 1 is provided with a transverse opening 9 in which is conformably received a sliding pin 10 the latter being carried by and operating in a hole 11 provided therefor in the half 2. Pin 10 has its inner end slightly enlarged as at 10' to prevent same from becoming disengaged from hole 11. Part 2 is further formed with a hollowed-out portion 12 across which extends a bridge 13. A catch 14 is carried by the part 1 which catch is adapted to enter the depression 12 and to pass above the bridge 13 when the parts are moved to locked position. When the parts are moved into closed position, the openings 9 and 11 will register as shown in Fig. 5, so that a slight tap with the finger will be sufficient to drive or move the pin 10 partly or wholly into the hole 11, thus holding the two parts against movement. Since the catch 14 resiliently engages the bridge 13 it will thus be seen that the parts will be held against movement thereby. To open the ring a slight tap is given to the same to return the pin into its hole 9 when the two parts may be moved in opposite direction to release the catch 14 from the bridge 13. Any matter such as will identify the wearer of the ring, or matter of any character whatsoever can obviously be engraved on or carried by the inner faces 3 and 4.

By reason of the two parts 1 and 2 being linked, they are inseparably connected, thus preventing loss of either of the parts when they are in open position. Further the pin 10 engages the walls formed by hole 9 remaining in position until the ring is tapped with the hand, or the like to cause the pin to enter its hole 11, thus freeing same from engagement with the part 2.

Having thus described my invention, I

claim as new and desire to secure by Letters Patent:—

1. A ring composed of two parts having abutting faces for engagement with each other, one of said parts carrying a freely sliding locking pin and the other of said parts having a hole to receive said pin when the parts are in normally closed position, the first-named part carrying a catch, 10 and the second-named part having a depression formed with a bridge over the same underneath which bridge the catch is adapted to engage.
2. In a ring, a plurality of parts and 15 means to lock the parts together, said means consisting of a catch member carried by the inner face of one of said parts, the other of said parts being formed with a depression to receive said catch, means carried by the 20 last named part to engage the catch, and

transverse locking means between the parts adapted when in locked position to prevent movement of the parts necessary to move the catch to unlocked position.

3. A ring composed of two parts having abutting faces for engagement with each other, means carried by the abutting faces of said parts to prevent said parts being moved away from each other in a lateral direction with respect to the plane of the 25 ring and means to prevent a sliding movement of said parts relative to each other.

In testimony whereof I have hereunto signed my name to this specification in the presence of two subscribing witnesses.

CAMILLO DINUCCIO.
